MOP AND MOP HANDLE

Filed Sept. 21, 1942

UNITED STATES PATENT OFFICE

2,320,291

MOP AND MOP HANDLE

Max Moskowitz, Bronx, N. Y.

Application September 21, 1942, Serial No. 459,171

1 Claim. (Cl. 15—153)

This invention relates to mops, and more particularly to an improved handle structure for a mop.

An object of this invention is to provide a mop handle structure which includes an elongated handle and an improved mop swab holder and clamping means.

Another object of this invention is to provide a mop handle structure which is so constructed that it may be made entirely out of wood or other non-critical material.

A further object of this invention is to provide a mop handle structure which is so formed as to provide a splash guard.

A further object of this invention is to provide in a device of this kind, an improved swab holder which includes an upper clamping member detachably secured to the handle, and a lower clamping member detachably secured to the upper clamping member, the opposite longitudinal sides of the upper clamping member having a configuration such as to form a splash guard.

To the foregoing objects, and to others which may hereinafter appear, the invention consists of the novel construction, combination and arrangement of parts as will be more specifically referred to and illustrated in the accompanying drawing, but it is to be understood that changes, variations and modifications may be resorted to which fall within the scope of the invention as claimed.

In the drawing:

Figure 1 is a sectional view, taken on the line 1—1 of Figure 2, showing an improved handle and mop swab holding structure constructed according to an embodiment of this invention;

Figure 2 is a sectional view taken on the line 2—2 of Figure 1;

Figure 3 is a fragmentary plan view of the swab;

Figure 4 is a fragmentary sectional view of a modified form of this invention; and

Figure 5 is a fragmentary sectional view of a further modification of this invention.

Referring to the drawing, the numeral 10 designates generally an upper clamping member which is rectangular in plan, and is provided with a threaded socket 11 opening through the upper side thereof, and inclined to the vertical. An elongated handle 12, which is formed with a threaded lower end 13, is threaded into the socket 11. The upper clamping member 10 is preferably formed out of wood and is provided along the longitudinal edges thereof with opposed splash guards, generally designated as 14 and 15.

The guards 14 and 15 are of like construction and are formed by cutting the longitudinal edges or sides of the body or clamp 10 as indicated at 16. The cut 16 is on a concave and merges at 5 its upper edge in a convex rib 17 which merges with the upper side of the upper clamp 10. The bottom face 17a of the upper clamp 10 is flat and the lower clamp 18 is adapted to be disposed in face abutting relation with the lower side 17a of the upper clamp 10. The lower clamp 18 is formed with a flat upper side 19 and a convex or transversely arcuate lower side 20. The upper side of the lower clamp 18 is provided with a longitudinally extending channel or recess 21 within which the webbing 22 of a mop swab 23 is adapted to engage. The swab 23 has a width substantially less than the length of the two clamp members 10 and 18, as shown in Figure 1.

The lower clamp 18 is detachably held in clamping position by means of a pair of bolts 24. The bolts 24 are extended through openings 25 formed in the upper clamp 10 exteriorly of the longitudinal edges of the swab 23 and closely adjacent the opposite ends of the two clamps. The bolts 24 are threaded into threaded sockets or openings 26 which are formed in the lower clamp 18. These bolts 24 may be formed of wood so that the entire clamp structure, including the handle 12, will be made out of wood.

30 The swab 23 is adapted to extend downwardly from the lower clamp 18 on the opposite longitudinal edges thereof, as shown in Figure 2, and when in use the two guards 14 and 15 provide a means to prevent liquids from splashing on the upper side of the upper clamp 10 and on the user of the device.

35 The convex lower side 20 of the lower clamp 18 provides an arcuate surface for permitting rocking of the clamp structure during the mopping operation.

40 Referring now to Figure 4, there is disclosed a mop and handle structure, similar to that shown in Figure 2, which includes an upper clamp 10a similar in every detail to the upper clamp 10, and also includes a lower clamp 18a similar to the lower clamp 18. A handle 12a is threaded into the upper side of the upper clamp 10a and a swab 23 is interposed between the two clamps 10a and 18a. In this form a pair of bolts 27 are extended through openings 28 formed in the lower clamp member 18a, and the bolts 27 have the heads 29 thereof countersunk in the arcuate lower side 20a of the lower clamp 18a. The bolts 27 are also extended through openings 30 formed in the upper clamp 10a which align with the

openings 28 and wing nuts 31 are threaded onto the threads of the bolts 27.

In the use of this mop structure the swab 23 is interposed between the two clamping members 10 and 18, and secured therebetween by the bolts 24. The mop structure may then be used in the conventional manner during which the splash guards 14 and 15 will operate to prevent or deter the splashing of the liquid, and lower arcuate side 20 of the lower clamp 18 will provide an arcuate surface which will be rocked during the sliding movement of the swab 23 over the surface which is being operated upon. During the use of the mop structure the swab 23 will be interposed between the surface worked upon and the arcuate lower side 20 of the clamp 18.

The modification shown in Figure 4 will operate in the same manner as that shown in Figures 1 and 2 with the exception that the bolts 27 will be loosely extended through the two clamping members and secured by the wing nuts 31. The bolts 27 are in the same relative position with respect to the two clamping members 10a and 18a as the bolts 24 with respect to the clamping members 10 and 18, as shown in Figure 1.

There is shown a further modification of this invention wherein the upper clamping member 10b has the handle 12b inserted in an unthreaded socket 11b. The handle 12b is formed with a transverse opening 32 within the socket 11b and a bolt or pin 33 is extended through an opening 34 which is formed transversely through the

clamping member 10b so that the bolt 33 may be extended through the opening 34 and the opening 32 in order to removably secure the handle 12b within the upper clamping member 10b. In other respects the structure shown in Figure 5 is similar in every detail to that shown in Figures 2 or 4.

I claim:

A mop handle and swab clamping structure comprising a handle, an elongated upper clamp secured to said handle, said upper clamp having a flat lower side substantially narrower than the upper side, a pair of outwardly projecting upwardly divergent splash guards integral with the opposite longitudinal edges of said upper clamp, each guard formed with a concave outer side, a lower clamp provided with a flat upper side having a longitudinal channel within which the web of the mop is adapted to engage and also provided with a convex lower side, the upper side of said lower clamp being of a width substantially equal to the width of the lower side of said upper clamp, said channel dividing said lower clamp into a pair of spaced clamping portions confronting the lower flat side of said upper clamp to thereby clamp the swab transversely of the latter at a pair of spaced points with the web loosely engaging in said channel, and a pair of bolts detachably securing said clamps together, said bolts being disposed outwardly of the opposite edges of the swab.

MAX MOSKOWITZ.
